J. A. MURDOCK

2,446,661

BOTTLE STOPPER

Filed Nov. 11, 1944

Inventor:
James A. Murdock,
By Dawson, Omsay & Booth,
Attorneys.

Specified in the claims and illustrated in the drawings, which are a part of this specification, the invention consists of the following:

1. A bottle closure for a bottle having a neck, comprising a plunger having a head member and a shaft, a cap member, a clasp member, an expander, an expansible stopper, a washer, a bridge, and a pair of spring clasps, the head member being reciprocable through the cap member and the clasp member, the lower end of the plunger being secured in the expander which normally rests in the expansible stopper, the expansible stopper having an annular flange which is retained between the washer and the top of the cap member when the parts are assembled as shown in Fig. 1.

2. A bottle closure for a bottle having a neck, comprising a plunger having a head member and a shaft, a cap member, a clasp member, an expander, an expansible stopper, a washer, a bridge, and a pair of spring clasps, the head member being reciprocable through the cap member and the clasp member, the lower end of the plunger being secured in the expander which normally rests in the expansible stopper, the expansible stopper having an annular flange which is retained between the washer and the top of the cap member when the parts are assembled as shown in Fig. 1.

UNITED STATES PATENT OFFICE

2,446,661

BOTTLE STOPPER

James A. Murdock, Chicago, Ill.; Iris M. Murdock, executrix of said James A. Murdock, deceased, assignor to Iris M. Murdock, individually

Application November 11, 1944, Serial No. 562,931

5 Claims. (Cl. 215—52)

1

This invention relates to a bottle stopper and has for its object the provision of a new type of bottle closure in which an expansible stopper is combined with a clasp device to mechanically lock the expansible member within the bottle mouth.

A further object of the invention is to provide an expansible bottle stopper which is not dependent upon the expansible plug alone to resist the pressure generated by the contents of the bottle but has a pair of spring clasps to lock the bottle stopper upon the external bead of a crown cap type bottle.

A further object of the invention is to provide a bottle closure which can be operated with three fingers simultaneously to release the expansible stopper and the clasps by which the stopper is held in its sealing position upon the mouth of the bottle.

A further object of the invention is to provide a bottle closure that may be repeatedly used without impairment of its sealing capacity.

The dispensing of carbonated beverages from bottles from which part of the contents is removed at one time and the remainder kept for later use has long presented a problem of sealing the remainder of the contents within the bottle without loss of the gas content of the liquid within the bottle. Various types of closures have been proposed as seals for the familiar crown cap type bottle in order to seal the bottle after the crown cap or seal has been removed. Most of the closures in use have been expansible rubber stoppers that engage the interior of the neck of the bottle and rely upon the friction of the rubber against the neck interior to prevent the pressure of the gas from forcing the stopper out of the bottle. Because the bottle neck was usually wet and because the bottle necks vary in interior dimensions this type of stopper has frequently been blown from the bottle neck by the pressure of the gas in the bottle and has resulted in loss of the bottle contents and occasionally injury to the user.

Other types of closures which have been dependent upon a spring pressed washer in contact with the upper edge of the bottle mouth have not been successful because of the variations in dimensions and contour of the bottle mouths.

It is the object of this invention to present a closure which is not dependent upon the friction of the expansible stopper within the bottle but provides a readily manipulatable clasp by which the expansible stopper may be locked in its sealing position. It is also the purpose of this inven-

tion to provide a combination stopper with a mechanical clasp and an expansible stopper which can be simultaneously operated in the application of the closure to the bottle and its removal therefrom.

These and other features of the invention will be seen from the following detailed specification read in connection with the accompanying drawings forming part thereof and in which—

10 Fig. 1 is a view in perspective of a preferred form of the bottle closure of this invention;

Fig. 2 is an exploded sectional view of the several elements of the bottle closure of this invention.

15 Fig. 3 is a sectional elevation of the bottle closure being applied to a bottle, a fragment of the bottle neck being shown in section;

Fig. 4 is a sectional elevation of the bottle closure after application to a bottle and in locked 20 sealing position, a fragment of the bottle neck being shown in section;

Fig. 5 is a sectional view of the bottle closure applied to a bottle mouth taken on the line 5—5 of Fig. 4.

25 Referring to the drawings the preferred form of the bottle closure of this invention is shown as an assembly of a plunger 10, a cap member 11, a clasp member 12, an expander 15, an expansible stopper 16, and a washer 18.

30 The plunger 10 is made up of a head member 9 and a shaft 8. This plunger is reciprocable through the cap member 11 and the clasp member 12 and has the lower end of the plunger secured in the expander 15 which normally rests in the expansible stopper 16. The expansible stopper 16 has an annular flange 17 which is retained between the washer 18 and the top of the cap member 11 when the parts are assembled as shown in Fig. 1.

35 40 A pair of spring clasps 13 adapted to engage diametrically opposed portions of the external bead or rim 25 of a bottle 24 are connected by a bridge 2. Each clasp 13 has an extension rebent upon itself which terminates in a finger piece 14 having a concavely curved underside surface.

The cap 11 is preferably formed with an embossed channel 19 impressed diametrically across the same to provide means for retaining the bridge 20 against movement peripherally of the cap 11.

45 50 This bridge 20 is held within the embossed channel 19 by means of the washer 18 which is retained within the cap by crimping the lower edge 21 of the cap about the washer 18 around the periphery of the cap except where the cap is cut 55 away at the ends of the embossed channel to

provide for the passage of the clasps 13 between the cap member 11 and the washer 18. The washer 18 is also notched in two places 22 to permit the passage of the clasps 13.

The plunger, cap, clasp member and washer may be made of suitable metals and the clasp member must necessarily be made of a flexible resilient metal so that it may perform as herein-after described.

The expander 15 may be made of metal, wood, fibre or other composition which will give it substantially uniform shape and permit it to hold the plunger 8 securely.

The expandable stopper 16 is preferably made of rubber so that it may readily be flexed and expanded and will resume its original shape when pressure upon it is released.

The various members of the bottle closure are assembled in the manner indicated by the sectional views Figs. 3 and 4 and the entire assembly can be secured together when the peripheral rim 21 of the cap member 11 is flanged about the washer 18 as best shown in Fig. 5.

Method of operation

When it is desired to use the closure on a crown cap type bottle provided with the usual externally beaded mouth, the closure is picked up with the finger pieces 14 held respectively by the first and second fingers of one hand and the thumb pressed against the cap 9 of the plunger 10. When the fingers are brought together the finger pieces 14 are drawn together to spread the clamp members 13, and the thumb forces the cap and plunger with the expander 15 down into the expandable stopper which is thereby radially contracted and deformed into a long slender configuration. With the closure held in the position shown in Fig. 3 it is lowered into the mouth of the bottle 23 until the washer 18 is brought against the lip 26 of the bottle mouth and the clasps 13 are brought beneath the edge of the external bead 25 as shown in Fig. 4.

With the closure held in this position, relaxation of the pressure upon the fingers permits the clasps 13 to come together beneath the bottle bead 25 mechanically to lock the closure upon the bottle mouth. Simultaneously the rubber stopper 16 shortens and expands bodily to engage an extended area of the interior of the bottle neck 24. Thereupon the expanded stopper seals the contents within the bottle and any pressure against the closure is transmitted through the stopper 16, expander 15, and the bridge 20 to force the clasps 13 together more tightly as the pressure increases.

To disengage the closure from the bottle mouth the first and second fingers are placed under the finger pieces 14 and the thumb again placed upon the plunger cap 9. As the two fingers are brought toward the thumb, the finger pieces approach each other, the clasps are spread and the expandable stopper is lengthened and radially contracted until the bottle stopper can be freely lifted from the bottle mouth.

Because of the resilient character of the bridge 20 and the finger pieces 14 and clasps 13, the clasp member 12 tends normally to grip the bottle bead tightly and this gripping action is increased with any pressure upon the lower surface of the expandable stopper and the bridge 20 by which the two clasps are connected.

The expandable stopper, because of its character tends to accommodate itself to any slight variations in the dimensions of the bottle neck and the mechanical locking means insures that

the wet surface of the interior of the bottle neck will not permit the expansible stopper to be forced therefrom by gas pressure within the bottle.

Having thus shown and described one embodiment of the invention, it is to be understood that it is capable of many modifications. Changes, therefore, in the construction and arrangement may be made without departing from the spirit and scope of the invention as disclosed in the appended claims, in which it is intended to claim all novelty inherent in the invention as broadly as permissible, in view of the prior art.

What is claimed is:

1. A closure for application to a bottle having an external bead about its mouth comprising a pair of spring clasps for engaging diametrically opposed portions of said external bead, an expandable stopper, a plunger mounted for movement toward and away from a position to contract said expandable stopper for inserting the latter within the mouth of said bottle, each of said clasps having an extension terminating in a finger piece conjointly presenting surfaces against which the fingers of a hand may be applied to spread said clasps while the thumb of the same hand is applied against the plunger to cause the latter to move toward a position to contract said expandable stopper.
2. A closure as claimed in claim 1 in which said spring clasps are connected by a bridge portion and said expandable stopper is secured to said bridge portion.
3. A closure as claimed in claim 1 in which said spring clasps are connected by a bridge portion and a cap to which said bridge portion is connected and a washer positioned opposite to the inner surface of said cap cooperate to secure the expandable stopper to the bridge connecting the spring clasps.
4. A closure as claimed in claim 1 in which said spring clasps are connected by a bridge portion and in which said expandable stopper is provided with an operating shaft which passes through a cap in which said bridge portion connecting said spring clasps is fastened against movement peripherally of the cap.

5. A closure as claimed in claim 1 in which said spring clasps are connected by a bridge portion and means cooperating with said expandable stopper to secure the latter to said spring clasps including a cap provided with a channel in which the bridge portion connecting the spring clasps is retained against movement peripherally of the cap.

55 JAMES A. MURDOCK.
